BURIAL VAULT

Claude R. Neff, Camden, Ohio, assignor to The Neff & Fry Company, Camden, Ohio, a Corporation of Ohio

Application May 12, 1932. Serial No. 610,830

8 Claims. (Cl. 72—7)

My invention relates to burial vaults. It has to do, more particularly, with a vault which may be used as a surface burial vault or which may be readily converted into various types of under-
5 ground burial vaults.

One of the objects of my invention is to provide a burial vault which may be used as a surface burial vault or which may be readily converted into an underground burial vault.

10 Another object of my invention is to provide a vault which may be made of concrete or other suitable material and which is of such a design that it can be manufactured at a relatively low cost.

15 Another object of my invention is to provide a surface burial vault which is made of several sections so that it can be readily handled and positioned in the desired place.

Another object of my invention is to provide 20 a vault having a casket chamber and a means consisting of a dead air chamber disposed above the casket chamber or a chamber filled with some suitable insulating material for insulating the casket chamber and a means for effectively 25 sealing the casket chamber and the insulating chamber.

In its preferred form, my invention contemplates the provision of a vault which consists of 30 of main body portion which is designed to form the casket chamber. A lid is provided for covering the upper end of this casket chamber and this lid is sealed thereon by a dual seal consisting of an air seal and a seal comprising some suitable sealing composition. I have also provided a chamber which is produced above the 35 casket chamber by mounting an inverted box-like structure on the lid of the casket chamber. This chamber may be a dead air chamber or may be filled with cork or some other insulating substance. This inverted box-like structure has its 40 lower end open and the lower edges of the walls thereof are adapted to fit into grooves formed on the upper surface of the casket chamber lid. Suitable sealing compound may be used for sealing 45 the inverted box-like structure on the lid of the casket chamber. A cover slab may be placed on the upper end of the inverted box-like structure although the top of the box-like structure 50 may be cast in such a manner that a cover slab will not be necessary. If desired, this cover slab may be provided with a suitable marker.

The preferred embodiment of my invention is shown in the accompanying drawings wherein 55 similar characters of reference designate corresponding parts and wherein:

Figure 1 is a perspective view showing a surface burial vault positioned in the ground, such vault being constructed in accordance with my invention.

Figure 2 is a longitudinal section of a burial 60 vault made in accordance with my invention and showing it after it has been positioned in the ground.

Figure 3 is a transverse section of a vault of 65 the type shown in Figures 1 and 2 and showing a casket in the casket chamber.

Figure 4 is a transverse section of a vault made in accordance with my invention having the dead air chamber omitted therefrom and being adapted to serve as an underground burial 70 vault.

Figure 5 is a transverse section of a vault similar to that shown in Figure 4 with the exception that in this instance the vault is provided with a slightly different form of lid which 75 is hinged to the upper end of the body portion of the vault.

Figure 6 is a transverse section of a vault similar to the type shown in Figures 4 and 5, and in this instance the body portion is shown 80 inverted over a slab on which the casket rests, and the closed end of the vault is in this instance the top of the vault.

With reference to the drawings, and particularly to Figures 1 to 3 inclusive, I have shown 85 a surface burial vault made in accordance with my invention. This vault may be constructed of any suitable material, preferably concrete, although it may be made of various plastic or other materials.

The vault comprises a body portion 1, which 90 is adapted to form a chamber 2 in which the casket is adapted to be placed. It will be understood that if this vault is made of concrete or other such material it may be suitably reinforced throughout although I have not shown such reinforcement. The body portion 1 comprises end walls 3 and 4, side walls 5 and 6 and the bottom 7, all being formed integrally with 95 each other. This chamber 2 may be of any suitable size and is preferably of such a size as to receive several different sizes of caskets. If desired, the inner surface of the bottom wall 7 100 may be provided with suitable supports 8 on which the casket is adapted to rest.

A lid 9 is provided for closing the upper end 105 of the casket chamber 2. This lid comprises a portion 10 which is adapted to extend over the entire upper end of the casket chamber and to cover such chamber. The portion 10 is provided 110

with a flange 11 which depends from the portion 10 a considerable distance and which is formed around the entire outer edge of the portion 10. It will be obvious that this flange may be 5 formed integral with the portion 10 or may be joined thereto in any suitable manner. When the cover 10 is positioned on the upper end of the body portion 1, a space 12 is provided between the inner surface of the flange 11 and the 10 outer surface of the upper end of the walls of the body portion 1. Before the lid 9 is placed on the upper end of the body portion 1, suitable sealing material 13 is preferably placed entirely around the upper edge of such body portion although it will not be necessary to use sealing 15 material at all, since the air seal produced between the lid and the body portion 1 will effectively seal the casket chamber, as will be apparent hereinafter.

20 It will be understood that when the lid 9 is mounted on the upper end of the body portion 1 the casket chamber 2 will be effectively sealed. This sealing is accomplished in two ways. It will be obvious that if water begins to ascend 25 into the space 12 it will compress the air therein and therefore, further movement of the water upwardly will be precluded. If no sealing compound is used between the lid 9 and the body portion 1, movement of water up into the space 30 12 will compress the air in such space and in the casket chamber itself so that further movement of the water will be precluded. In other words, the lid 9 in cooperation with the body portion 1 forms an air seal which will prevent 35 entrance of moisture into the casket chamber.

The sealing compound 13 when used will also aid in preventing moisture from entering the casket chamber 2 and will also preclude the 40 passage of air thereinto. By sealing the lid 9 to the body portion 1 with a suitable compound these units will be so bound together that they will practically be the same as one unit, thus offering a great handicap to anyone trying to 45 steal the casket.

I have provided a member 14 which is of substantially the shape of a box and which comprises side walls 15 and 16, end walls 17 and 18, and a top wall 19. The lower end of this box-like structure is open. The lower edges of the 50 walls of this box-like structure are adapted to fit into a groove 20 which is formed in the upper surface of the portion 10 of the lid 9. When this member 14 is mounted on the lid 9 as shown in the drawings, it is adapted to produce a chamber 21 above the casket chamber 2. This 55 chamber is preferably a dead air chamber but may be filled with cork or other suitable insulating substances. A suitable sealing compound 22 may be disposed in the groove 20 around the lower edge of the walls of the member 14. This sealing compound is adapted to preclude entrance of air or moisture into the insulating chamber 21 and to preclude escape of air therefrom.

60 A cover slab 23 is adapted to be mounted on the upper surface of the top wall 19 of the member 14. This cover slab may consist of a slab of marble, granite or other such material, or may consist of a slab of pre-cast material which is suitably mounted thereon. If desired, the slab 23 may be cast integral with the member 14. It will be obvious that this slab may be made of numerous materials and in various forms. If desired, a bronze marker 24, or a marker of 65 aluminum, granite, marble or any other suitable

material, may be mounted on one end of the slab 23. It will also be obvious that a head stone may be provided which may be mounted on the member 14 or slab 23 or may have its lower end underground and resting on one end of the lid 9.

It will be obvious that the body portion 1 is first placed in the grave and the casket is then lowered thereinto. The lid 9 is then positioned on the upper end of the casket chamber. The member 14 is then mounted on the lid 9 and if the slab 23 is formed separate therefrom, it is then placed thereon. The vault is then buried with the upper end of the member 14 level with the surface of the surrounding ground. If a slab is not used and the portion 23 is cast integral with the member 14 such portion will protrude above the ground.

It will be obvious that the cover slab 23 or the portion 23 which is cast integral with the member 14, not only serves to increase the attractiveness of the vault but also provides a heavy absorbing surface which will absorb the heat or cold from the outer air to prevent the dead air chamber or insulating chamber 21 from being materially affected thereby. The dead air chamber or insulating chamber 21 will form a very effective insulation means between the outside air and the casket chamber 2. Thus, an even temperature will be maintained in the casket chamber and the casket cannot possibly be affected by outer air conditions and the corpse in the casket will keep indefinitely. The action of the sun or warmth upon the exposed part of the burial vault, due to capillary attraction, tends to draw any moisture in the casket chamber 2 from such chamber through the lid 9 into the insulating chamber 21, and then from the insulating chamber through the top of member 14 and through member 23 out into the atmosphere. Thus, since no moisture can enter the casket chamber 2, the moisture contained in the body itself will be eventually extracted, thereby eliminating disintegration.

It will also be understood that my complete 120 surface vault is made of three main sections, namely, the body portion 1, the lid portion 9, and the member 14. It will be obvious that since the vault is constructed in this manner it may be readily handled and positioned in the grave.

In Figure 4, I have shown a vault which may consist of the body portion 1 and the lid 9 of the vault shown in Figures 1 to 3 inclusive. In this instance the member 14 is not used and the vault merely consists of a casket chamber without having a dead-air chamber or insulating chamber thereabove. This vault is adapted to be buried underground. It will be obvious that the casket chamber is identical with that shown in the surface type and that it will be effectively sealed in the same manner.

In Figure 5, I have shown a slightly different form of underground burial vault. This vault comprises the body portion 1 which is identical with that shown in Figures 1 to 4 inclusive. However, this vault is provided with a slightly different form of cover. This cover comprises an arched member 25 which is hinged to the body portion 1 by hinge members as at 26. The cover is provided with depending flanges 27 which extend entirely around the inner surface of the upper edge of the walls of the body portion 1. Sealing material 28 is disposed between the upper edges of the walls of the body portion 1 and the cover. It will also

be obvious that the cover is constructed in such a manner and cooperates with the upper edge of the body portion 1 in such a manner, that an air seal will also be produced.

5 Figure 6 shows another form of underground burial vault. This vault comprises a body portion 1 similar to that shown in the preceding figures and which may be cast in the same mold as the body portion of the vaults previously described. The body portion 1 may be inverted and disposed over a slab 29 which is provided with depending flanges 30 which are adapted to rest on the floor of the grave. The casket is adapted to rest on the slab 29 and the body portion 1 is adapted to entirely enclose such casket. The upper end of the body portion 1 may be provided with a flat top as shown by the dotted lines or an arched top as shown by the full line. It will be obvious 10 that it will not be necessary to seal the slab 29 to the body portion 1 as an air seal will be produced between the edges of the slab and the walls of the body portion 1.

It will be understood that the surface vault made in accordance with my invention may be readily converted into various types of underground burial vaults. It will also be understood that in the casting of these vaults, the same identical mold may be used in forming all of 25 the various types with the exception of the type shown in Figure 6 which is provided with the arched upper end. In this instance, it will be necessary to use an arched plate in the bottom of the mold.

30 Having thus described my invention, what I claim is:

1. A surface burial vault comprising a body portion adapted to form the casket chamber, a lid mounted on the upper end of said body portion, said lid being provided with a continuous depending flange adapted to form an air seal between said lid and said body portion and being situated on the outside of said body portion, sealing compound disposed between said lid and said body portion, a removable member mounted on said lid, said member comprising an inverted substantially box-like structure, said structure having its lower edges fitting into a groove formed in the upper surface of said lid.

2. A surface burial vault comprising a body portion adapted to form the casket chamber, a lid mounted on the upper end of said body portion, said lid being provided with a depending flange adapted to form an air seal between said lid and said body portion, sealing compound disposed between said lid and said body portion, a removable member mounted on said lid, said member comprising an inverted substantially box-like structure, said structure having its lower edges fitting into a groove formed in the upper surface of said lid, a sealing compound disposed in said groove around the lower edge of said structure, and a cover slab mounted on the upper end of said structure.

3. A burial vault comprising a body portion adapted to form a casket chamber, a lid mounted on the upper end of said body portion and

having a depending flange adapted to surround the upper end of said body portion, an inverted box-like structure mounted on the upper surface of said lid, said box-like structure being of substantially less area than said lid so that a portion of said lid is left uncovered by said box-like structure.

4. A burial vault comprising a body portion of substantially rectangular cross-section, a lid mounted on the upper end of said body portion and having a depending flange which will lie entirely around the upper end of said body portion but which will be spaced from the outer surface thereof, an inverted box-like structure removably mounted on the upper surface of said lid, said box-like structure having its lower edges fitting into a groove formed in the upper surface of said lid, and said box-like structure being of substantially less area than said lid.

5. A burial vault comprising a hollow body portion adapted to form a casket chamber, a lid mounted upon the upper end of said casket chamber, said lid being provided with a continuous depending flange adapted to form an air seal between said lid and said body portion, and a hollow member mounted on said lid adapted to form an insulating chamber above said casket chamber and attached in an air tight manner to said lid.

6. A burial vault comprising a hollow body portion adapted to form a casket chamber, a lid mounted upon the upper end of said casket chamber, said lid being provided with a continuous depending flange adapted to form an air seal between said lid and said body portion, and a hollow member mounted on said lid adapted to form an insulating chamber above said casket chamber and attached in an air tight manner to said lid, said member being substantially of less area than said body portion.

7. A burial vault comprising a body portion, a chamber formed in said body portion and adapted to receive a casket, the upper end of said casket chamber being open, a lid mounted on the upper end of said body portion for completely closing the upper end of said casket chamber, said lid comprising a main portion having a downwardly extending flange disposed entirely around the edges thereof, said flange extending downwardly over the upper portion of said body portion for a considerable distance and completely surrounding the upper end of said body portion and being spaced from the walls of said body portion so that a chamber is formed between the inner walls of said flange and the outer walls of said body portion, said last named chamber having its upper end closed and its lower end open so that an air seal is formed between said lid and said body portion.

8. A burial vault comprising a hollow body portion adapted to form a casket chamber, a lid mounted upon the upper end of said casket chamber, said lid being provided with a continuous depending flange adapted to form an air seal between said lid and said body portion, and a hollow member mounted on said lid adapted to form an insulating chamber above said casket chamber, said hollow member being air tight.

CLAUDE R. NEFF.
